DEVICE FOR USE IN MAKING CROSS
SECTIONS OF FIBERS

John I. Hardy, Washington, D. C.

Application April 23, 1935, Serial No. 17,834

8 Claims. (Cl. 88—40)

(Granted under the act of March 3, 1883, as
amended April 30, 1928; 370 O. G. 757)

This application is made under the act approved March 3, 1883, as amended by the act of April 30, 1928; and the invention herein described, if patented, may be manufactured and used by or for the Government for governmental purposes without the payment to me of any royalty thereon.

This invention relates to a device having a fiber slot for use in rapidly making cross sections 10 of wool and other fibers.

The rapid methods ordinarily used for making thin cross sections of fibers involve the use of a piece of cork or elder-pith.

In case a piece of cork or elder-pith is used the 15 fibers are threaded through a small perforation by the use of a needle. The cross section of fibers is obtained by cutting the fibers close to the surfaces of the cork or elder-pith, by means of a sharp instrument. The disadvantages of these 20 methods are due to the time consumed in passing the fibers through the cork and to the fact that the individual fibers are doubled in the process. It is also found in drawing the fibers through a piece 25 of cork or elder-pith that the tension exerted often breaks or distorts the shape of the fibers. Furthermore, the thickness of the section cannot be accurately controlled and very thin sections are rarely obtainable.

The objects of my present device are to obtain 30 good, thin, cross sections of fibers more rapidly and at the same time to eliminate the disadvantages of existing methods as disclosed above.

I attain these objects by use of the device illustrated in the accompanying drawing, in which 35 Figure 1 is a side view of the assembled device and Figure 2 is a cross sectional view of the entire device.

The device involves the use of a circular head 1 called the cutting head, preferably made of 40 metal, one end of which has a centered flat surfaced metallic extension 12. Threaded hole 2 of preferred size passes longitudinally through the center of the head 1 for approximately one-half the length of the head. The balance of the head 45 is hollowed out thereby forming sleeve 9. The sleeve end of the head 1, on its outer surface is graduated at its base 5. The circular supporting holder 6 is somewhat larger in diameter for about one-half its length than head 1 and bears a circular recessed portion 8 adapted to receive 50 sleeve 9 of head 1. The balance 13 of the supporting holder 6 adjoining the recessed portion is reduced in diameter so as to enter the hollowed portion of head 1 formed by the sleeve 9. Threaded hole 14 similar to threaded hole 2 in head 1, 55 passes longitudinally through the center of sup-

porting holder 6. The outer surface of holder 6 adjoining the graduation on the sleeve 9 in the assembled device bears a vernier graduation 7. Rod 3 as used by me is made of celluloid and is threaded to enter threaded holes 2 and 14 of head 1 and holder 6 respectively. Rod 3 bears a fiber slot 4 extending lengthwise of the rod. Lock nut 10 is formed to coincide in shape with the other end of holder 6 and a threaded hole 15 passes through its center longitudinally, such 10 hole being adapted to receive threaded rod 3.

It will be observed that the threaded rod 3 although ordinarily made of celluloid, or some such substance for convenience, may be made of almost any material. If wood, metal, etc. are used for the rod it would be necessary to use a plastic or adhesive material, such as a celluloid solution or a celluloid wedge and suitable solvent, to hold the fiber in the slot. When a hard material, such as metal is used for the rod, the cutting 20 of the cross sections would of course be more difficult and require a sufficient cutting instrument such as a saw for example.

To operate the device the rod 3 is placed in threaded hole 14 of holder 6, the ends of the rod 25 extending from both ends of the holder for the desired length. A single hair or fiber or small group of hairs or fibers are inserted in the fiber slot 4 of the threaded rod 3. The fiber is held in the slot by flowing a sufficient quantity of celluloid 30 solvent into the fiber slot to cover the fibers and fill the slot near the end of the rod which is to enter head 1. A piece of celluloid or other material of a size just sufficient to fill the slot up to the base of the threaded rod may be placed in the slot as a wedge to hold the fibers in a longitudinal 35 position in the fiber slot. The threaded rod is cut away with a sharp instrument on both sides of the fiber slot. The fiber slot in which the fibers are held is now at the apex of a triangular 40 shaped piece of material, with only a little material holding the fibers on three sides. The threaded rod 3 is adjusted in the threaded hole 2 of the head 1 to extend somewhat beyond the 45 face of the head as shown in Figure 1 and the lock nut 10 is screwed on to the other end of the rod against the supporting holder 6 until there is a tight fit where they come together at 11. The supporting holder 6 and the lock nut 10 then 50 serve as a handle for the entire device. By means 55 of a safety razor blade the threaded rod 3 containing the fiber slot and the embedded fiber is cut flush with the extended surface of the metal head, to approximately the center of the threaded rod 3, that is sufficiently to cut beyond the fiber 60

slot. This cut portion is removed by being cut free with a sharp instrument, thereby leaving a shoulder on the threaded rod 3 about half way across the rod. By means of the graduations on the metal head 1 and the supporting holder 6 the threaded rod 3 may be advanced according to the thickness required for the cross section. The cross section is cut off with a sharp razor, cutting closely to the surface of the cutting head, 10 mounted on a microscope slide, covered with a mounting medium and a cover slip, and is ready for microscopic examination. This device is especially intended for cutting of individual fibers for identification purposes, but may be 15 used for cutting groups of hairs or fibers.

From the above disclosures it will be apparent that minor mechanical variations may be made in the structure of the device without departing from the spirit of the invention.

20 Having fully disclosed my invention I claim.

1. A device for use in making cross sections of fibers comprising a cutting head having at one end a centered hard flat surfaced extension and a threaded hole passing longitudinally through its center for approximately one-half its length, the balance of its length being hollowed out to an extent greater than the diameter of the threaded hole, whereby a sleeve is formed at the other end of said cutting head, a supporting member having a threaded hole through its center longitudinally, a reduced extended portion at one end adapted to enter the hollowed portion of the cutting head and a recessed portion to receive said sleeve of the cutting head, a threaded rod adapted to be inserted in both said threaded holes and having a longitudinally placed fiber slot, a lock nut adjacent the other end of the supporting member adapted to receive the threaded rod and means to measure the movement of said threaded 40 rod in the threaded hole of the cutting head.

2. A device for use in making cross sections of fibers comprising a cutting head having a threaded hole through its center longitudinally, a threaded rod having a longitudinally placed fiber slot and adapted to enter and extend through

said threaded hole, means to support the threaded rod in the threaded hole and means to measure the extension of the threaded rod beyond the free end of the cutting head.

3. In a device for use in making cross sections of fibers having supporting members with threaded perforations, a threaded rod adapted to enter and extend through said perforations and having a fiber slot passing along the side of said threaded rod. 5

4. In a device for use in making cross sections of fibers having supporting members with threaded perforations, a threaded celluloid rod adapted to enter and extend through said perforations and having a fiber slot passing longitudinally 15 along the said threaded rod.

5. In a device for use in making cross sections of fibers having a perforated supporting member, a rod adapted to enter and extend through such perforation in the supporting member, said rod 20 having a fiber slot along its side.

6. In a device for use in making cross sections of fibers having a perforated supporting member, a celluloid rod adapted to enter and extend through such perforation in the supporting member, 25 said celluloid rod having a fiber slot along its side.

7. A device for use in making cross sections of fibers comprising a cutting head having a hole passing longitudinally through its center, a rod 30 having a longitudinally placed fiber slot and adapted to enter and extend through said hole in the cutting head, means to support the rod in the hole and means to measure the movement of the rod in the hole. 35

8. A device for use in making cross sections of fibers comprising a cutting head having a hole passing longitudinally through its center, a celluloid rod having a fiber slot along its side and 40 adapted to enter and extend through said hole in the cutting head, means to support the rod in the hole and means to measure the movement of the rod in the hole. 45
